UNITED STATES PATENT OFFICE

2,043,712

SEWING MACHINE

George Sauer, Berwyn, Ill., assignor to Union
Special Machine Company, Chicago, Ill., a cor-
poration of Illinois

Application April 3, 1934, Serial No. 718,855

7 Claims. (Cl. 112—256)

The invention relates to new and useful im-
provements in sewing machines, and more par-
ticularly to the construction of the housing for
the operating parts of the stitching mechanism
and the feeding mechanism, and the means for
5 providing lubrication therefor.

An object of the invention is to provide a sewing
machine wherein the main actuating shaft
and the immediate parts operated thereby are
10 disposed within a closed housing having an oil
bath at the lower portion thereof, and wherein
said shaft is provided with means disposed so as
to be partly immersed in the oil bath so that oil
adhering thereto will be thrown therefrom by
15 centrifugal force for creating a mist of oil within
the housing for lubricating the operating parts
disposed therein.

In the drawings which show by way of illus-
tration one embodiment of the invention—

20 Figure 1 is a vertical sectional view through a
sewing machine embodying the improvements,
and

Fig. 2 is a sectional view on the line 2—2 of
Fig. 1.

25 It is very important in a sewing machine that
the actuated parts be well housed so as to pre-
vent lubricating oil used in connection with said
actuated parts from being thrown on to the
fabric being stitched. This is particularly true
30 of the cup feed type of machine, wherein the
feeding mechanism and the stitching mech-
anism is, to a large extent, located wholly above
the fabric sections which are being stitched. The
present invention has to do with a construction
35 of housing and a lubricating system whereby the
actuated parts are freely lubricated and, at the
same time, the fabric being stitched is protected
so that no lubricating oil is thrown thereon. In
the drawings there is shown an illustrated em-
40 bodiment of the invention as applied to a cup feed
type of machine. The machine includes a hous-
ing which is closed and which contains practically
all of the actuating parts for the various elements
of the sewing machine. The housing includes a
45 base portion 1 which is mounted on a suitable
support, and rising from this base portion 1 is a
standard 2, at the upper end of which is a lat-
erally projecting portion 3. Mounted in this lat-
erally projecting portion 3 is a sleeve 4 in which
is mounted a shaft, and at the lower end of the
shaft is a feed cup 5 which is fixed to the shaft
and rotated thereby. Also mounted in this lat-
erally projecting portion of the housing is a bush-
ing 6, through which the shaft section 7 extends.
Attached to the shaft section 7 is a gear wheel 8

which meshes with a gear wheel 9 that is attached
to the shaft carrying the inner feed cup 5. Mounted on the laterally projecting portion 3 of
the housing is a bracket arm 10 carrying the
sleeve 11 in which is mounted a shaft section car-
rying the feed cup 12. The upper end of the
shaft section carrying the feed cup 12 is connected
through a universal joint 13 with the shaft sec-
tion 7. The bracket can be swung on its pivot for
separating the feed cups. The shaft carrying 5
the gear wheel 9 is actuated by the clutch feed
which in turn is oscillated by a link 14. This link
14 receives its endwise movement from an ec-
centric strap 15 cooperating with an eccentric on
the main actuating shaft 16. The main actu-
ating shaft 16 extends through the standard por-
tion of the housing and is mounted in suitable
bearings carried thereby. The bearing for the
main actuating shaft is in the form of a sleeve 17
10 which is secured to the housing by screws 18. 20
This sleeve carries a bushing 19, and the main
actuating shaft extends through these bushings
19. The sleeves at the opposite sides of the hous-
ing are similar in construction, and the one at
the left, in Fig. 2, is the only one which is shown
25 in section. The sleeve is provided with a recess 20
having a wall which inclines downwardly toward
the chamber within the housing. The sleeve 17
is also provided with a groove 49 which communi-
cates with the recess 20. The groove 49 is formed
30 with a wall portion inclined outwardly toward the
shaft 16 which carries a belt pulley 50 having an
integral collar portion 51 extending into the
groove 49 in the sleeve 17. This collar portion
51 is provided with peripheral inclined flanges 52
35 so that any oil working out of the bushing will
be thrown by the flanges 52 into the groove 49
from which it will drain back into the housing
through the recess 20.

The housing, as clearly shown in Figures 1 and
2, is provided with a bottom wall 21 which is dis-
posed at some little distance from the extreme
bottom edge of the base of the housing. This
bottom wall is formed integral with the side walls
of the housing and forms therewith a chamber 45
in which the oil bath may be maintained at the
bottom of the chamber. The oil bath extends up
to the broken line in Fig. 2, which is at a slight
distance below the actuating shaft and the sleeve
bearings therefor.

50 The fabric being stitched is placed between the
feed cups with the edge portions thereof pro-
jecting above the feed cups. The needle carried
by a needle bar 22 reciprocates across the feed
cups, penetrating the fabric edges and placing 55

a loop of thread therethrough. This needle bar is moved back and forth by a link 23 which is connected to a crank 24 on the main actuating shaft 16. The needle bar reciprocates in a bushing 25 located in an opening formed in the front wall of the housing. The bushing completely fills the opening. The bushing, as shown in Fig. 1, is provided with a recess from which a port 26 leads back into the chamber of the housing, so that any oil thrown against the inner end of the bushing may work into the bushing and lubricate the parts with which the needle bar contacts, but the recess will prevent the oil from working all the way through the bushing, as it will trap and return any excess oil which may be carried into the bushing by the reciprocating needle bar. Through this construction of bushing, the needle bar and the actuating parts therefor may operate in a mist of lubricating oil without any danger of the oil working through the bushing and being thrown by the reciprocations of the needle bar on to the fabric.

Cooperating with the needle is a looper 27. Said looper is carried by a bar 28 which is mounted for oscillation and reciprocation in a bushing 29. This bushing completely closes the opening through the front wall, so that the looper bar may be thoroughly lubricated through the application of a mist of oil thereto, without any danger of the oil flowing along the looper bar and being thrown thereby against the fabric. This bushing 29 is provided with a recess for trapping any excess oil which works into the bushing.

The looper bar 28 is moved endwise by means of an arm 30 fixed to a sleeve 31 which is mounted for oscillation on a shaft 32. Between the sleeve and the shaft is a bushing 33. Oil ports 34 lead through the sleeve and bushing so that a mist of oil within the housing may pass into said ports and lubricate the surface between the bushing and the shaft. The shaft is stationary. The shaft extends through bearing bosses 35 formed in the wall of the standard portion of the housing. Headed bolts 36 are threaded into the shaft and bear against a sealing gasket 37. This forms a tight seal for the shaft so that there is no chance for the lubricating oil to work out through the mounting for this shaft on which the sleeve is supported. The sleeve is held from endwise movement on the shaft by a collar 38. Attached to this sleeve 31 is an arm 39 carrying a ball stud 40. A link 41 is attached to the ball stud and cooperates with a crank 42 on the main actuating shaft 16.

The looper bar 28 is provided with a fixed collar 53 having a laterally extending ball stud 54 which is connected by a link 55 to an eccentric member 56 carried by the main shaft 16. By this mechanism, the looper bar is oscillated about its axis during the endwise movement thereof. In order to restrain the link from any tendency to twist, the ball stud 54 is provided with a pin 57 which is engaged by a forked member 58 carried by the link.

Cooperating with the looper and needle is a spreader 43. This spreader 43 is carried by a spreader bar which is mounted for reciprocation in a bushing 44. The bushing 44 closes an opening in the front wall of the standard of the housing, and this bushing is constructed similar to the bushing which supports the looper bar. This spreader bar does not have any endwise movement. It is oscillated only. The spreader bar is indicated at 45 in Fig. 2. Attached to the

upper end of said spreader bar is a sleeve 46 carrying a projecting arm provided with a bail stud, and an eccentric strap 47 cooperating with the bail stud also cooperates with an eccentric on the main actuating shaft 16.

From the above it will be noted that the fabric supporting means is disposed exteriorly of the housing. The shafts which support the feed cups extend through bushings or sleeves closing openings in the wall of the housing and the actuating parts for these shafts are completely enclosed within the housing. These feed cups which form the feeding mechanism are, therefore, operated from the main actuating shaft by actuated members completely enclosed within the housing and in a chamber extending all the way from the oil bath at the bottom of the housing to the extreme upper portion of the housing in which the operating gears and the feed clutch are mounted. The stitch forming mechanism, including the needle, the looper and the spreader, are each operated from an actuating shaft through actuated parts located wholly within this chamber in the housing.

Mounted on the actuating shaft 16 is a disk 48 which is preferably of uniform radius. The disk is so dimensioned that the lower portion thereof is immersed in the oil bath. As parts of the disk pass into the oil bath, oil will adhere thereto, and as these parts carrying the adhering oil leave the bath, the centrifugal force operating on the oil will cause it to move out to the peripheral edge of the disk and be thrown therefrom. The oil thrown from the disk striking the parts within the housing and the walls of the housing will form a mist or spray of oil, completely filling the whole chamber, so that all of these operated parts within the chamber will be thoroughly lubricated. The oil will drain back into the sump or oil bath at the bottom of the housing. From Figures 1 and 2, it will be noted that the actuating shaft and the cranks carried thereby are all located above the oil bath. At no time do the cranks contact with the oil, and there is, therefore, no beating of the oil by the rotating parts. When the oil is beaten to a froth by the rotating parts striking the same, heat is generated which has a deteriorating effect upon the oil. The disk extending down into the oil makes continuous contact therewith, and therefore, there is no stirring of the oil by the disk which serves to take up the oil and throw it in the form of a mist throughout the casing. Furthermore, the oil is not agitated by the disk or any other moving parts, and therefore, the sediment forming in the oil is allowed to settle and remain in the bottom of the sump.

While the invention is described as embodied in a machine having feed cups, it will be understood that the oil distributing means may be used in connection with other types of sewing machines where the actuated parts are enclosed within a housing, so that oil thrown by this rotating disk will not be thrown on to the fabric. The particular stitch forming elements illustrated, and the particular feeding mechanism illustrated, per se, form no part of the present invention. They have been illustrated for the purpose of showing one way whereby the actuated parts for the stitch forming mechanism and the feeding mechanism, and the actuating shaft therefor, may be completely enclosed within a housing and efficiently lubricated.

Having thus described the invention, what I claim as new and desire to secure by Letters Patent, is—

1. A sewing machine comprising a closed housing having an oil bath in the lower portion thereof, means disposed exteriorly thereof for supporting the fabric for stitching, a feeding mechanism, 5 a stitch forming mechanism, an actuating shaft extending through said housing above the surface of the oil bath, devices extending into said closed housing and operated by said shaft for actuating said feeding mechanism and for actuating said stitch forming mechanism, and means fixed to said shaft within said housing and disposed so as to be partly immersed in the oil bath whereby oil adhering thereto will be thrown therefrom by centrifugal force for lubricating the 10 operating parts within said housing.
2. A sewing machine comprising a closed housing having an oil bath in the lower portion thereof, means disposed exteriorly thereof for supporting the fabric for stitching, a feeding mechanism, a stitch forming mechanism, an actuating shaft extending through said housing above the surface of the oil bath, devices extending into said closed housing and operated by said shaft for actuating said feeding mechanism and for 15 actuating said stitch forming mechanism, and a disk fixed to said shaft within said housing and disposed so as to be partly immersed in the oil bath whereby oil adhering thereto will be thrown therefrom by centrifugal force for lubricating the 20 operating parts within the housing.
3. A sewing machine comprising a closed housing having an oil bath in the lower portion thereof, said housing having a laterally projecting portion forming a chamber communicating with a 25 chamber in the housing, feed cups for supporting fabrics carried by said laterally projecting portion of the housing, actuating means for the feed cups located in the chamber in said laterally projecting portion of the housing, an actuating shaft extending through the housing above the surface of the oil bath, stitch forming mechanism including a needle, a looper and a spreader, a bar to which said needle is attached, a bar to which the looper is attached and a bar to which 30 the spreader is attached, each of said bars extending through the wall of the housing and located in a bushing closing an opening through the wall, actuating means operated by said shaft for each of said bars, and means fixed to the shaft within 35 the housing and disposed so as to be partly immersed in the oil bath whereby oil adhering thereto will be thrown therefrom by centrifugal force for lubricating the operating parts within the chamber in the housing and in the laterally projecting portion thereof.
4. A sewing machine comprising a closed housing having an oil bath in the lower portion thereof, said housing having a laterally projecting portion forming a chamber communicating with a 40 chamber in the housing, feed cups for supporting fabrics carried by said laterally projecting portion of the housing, actuating means for the feed cups located in the chamber in said laterally projecting portion of the housing, an actuating shaft extending through the housing above the surface of the oil bath, stitch forming mechanism including a needle, a looper and a spreader, a bar to which said needle is attached, a bar to which 45 the looper is attached and a bar to which the spreader is attached, each of said bars extending through the wall of the housing and located in a bushing closing an opening through the wall, actuating means operated by said shaft for each of said bars, and means fixed to the shaft within 50 the housing and disposed so as to be partly immersed in the oil bath whereby oil adhering thereto will be thrown therefrom by centrifugal force for lubricating the operating parts within the chamber in the housing and in the laterally projecting portion thereof.
5. A sewing machine comprising a housing, a main actuating shaft extending into said housing, said housing having a projecting portion, 55 feed cups suspended from said projecting portion, an operating means for said feed cups enclosed within said projecting portion of the housing, a needle bar projecting through an opening in the front wall of the housing, a bushing in said opening in which said needle bar reciprocates, a looper bar extending through an opening in the front wall of the housing, a bushing in said opening in which said looper bar reciprocates and oscillates, a spreader bar extending through an 60 opening in the front wall of said housing, a bushing in said opening in which said spreader bar oscillates, said bushings being constructed so as to close the openings through the front wall of the housing, and a disk carried by said actuating 65 shaft and disposed so that the lower portion thereof extends beneath the surface of a bath of oil and whereby the oil thrown from the periphery thereof will lubricate all of the moving parts within said housing.
6. A sewing machine comprising a frame having an oiltight compartment with an oil bath in the lower portion thereof, a feeding mechanism, a stitching mechanism, a rotating shaft extending through said compartment, devices carried by 70 said shaft in said compartment for actuating the stitching mechanism and actuating the feeding mechanism, said shaft and said devices being all disposed above and out of contact with said oil bath, and a member fixed to said shaft within 75 said compartment and having all points of its periphery an equal distance from the axis of said shaft, said member being disposed so as to be partially and continuously immersed in the oil bath whereby the actuating devices are lubricated by oil distributed by centrifugal force from 80 said member.
7. A sewing machine comprising a frame having an oiltight compartment with an oil bath in the lower portion thereof, a stitching mechanism, 85 a rotating shaft extending through said compartment, devices carried by said shaft in said compartment for operating the stitching mechanism, said shaft and said devices being all disposed above and out of contact with the oil bath, and a member fixed to said shaft within 90 said compartment and having all points of its periphery an equal distance from the axis of said shaft, said member being disposed so as to be partially and continuously immersed in the oil bath whereby the actuating devices are lubricated by oil distributed by centrifugal force from 95 said member.

GEORGE SAUER.
